PORTABLE TELEVISION CART

Walter Gusdorf, 1042 Orchard Lakes, Creve Coeur, Mo.

Filed June 17, 1963, Ser. No. 75,365

Term of patent 14 years

(Cl. D33—3)

FIG.3

FIG. 1 is a front elevational view of a portable television cart showing my new design;

FIG. 2 is a side elevational view taken at the right side of FIG. 1, and

FIG. 3 is a perspective view of the portable television cart showing the opposite side thereof.

I claim:

The ornamental design for a portable television cart, substantially as shown.
